UNITED STATES PATENT OFFICE.

THOMAS E. BROWN, OF NEW YORK, N. Y.

BASCULE BRIDGE.

1,302,302.

Specification of Letters Patent. Patented Apr. 29, 1919

Application filed November 13, 1916. Serial No. 131,174.

To all whom it may concern:

Be it known that I, THOMAS E. BROWN, a citizen of the United States, and a resident of the borough of Manhattan, city of New York, in the county of New York and State of New York, have invented certain new and useful Improvements in Bascule-Bridges, of which the following is a specification.

10 This invention relates to improvements in bascule bridges.

The simplest form of a bascule bridge is the ordinary heel counter-balanced trunnion type, and this form is usually adopted when 15 the height of the bridge above the water is sufficient to admit of its use. In many situations, however, the height is insufficient for the heel of the bridge and counter-balance to clear the water or tops of the piers, and 20 in such cases the span must be made longer in proportion to the width of the waterway and a watertight pit must be provided into which the heel of the bridge and counter-balance may descend. The expense of construction in such cases becomes very great, 25 and therefore the more complicated and unsightly types, with towers and counterweights above the roadway, are usually resorted to.

30 Cases frequently occur where the height above water is not sufficient for a simple heel balanced bridge of ordinary type, without watertight pits, and yet where the use of unsightly towers and counterweights would 35 be very objectionable. In ordinary heel counter-balanced trunnion bridges it is necessary to so dispose the counter-balance that the center of gravity of the entire moving mass will coincide with the center of the

40 trunnion or pivot and this usually requires the placing of a considerable portion of the counter-balance above the bridge deck, to the detriment of the appearance of the structure; and it is therefore an object of my invention to produce a heel balanced trunnion bridge, suitable for such cases, in which 45 coincidence of the center of gravity and the pivot is unnecessary and wherein no counter-balance need to be placed above the deck 50 of the bridge, and by which also the use of watertight pits or unsightly towers is entirely avoided.

To accomplish this, I prefer to partially

balance the bridge by heel counter-balance, *i. e.* heavy material placed in the heel of the 55 bridge, using as much heel counter-balance as the height above water will conveniently permit, and complete the balance of the moving span by means of a counter-weight pivoted to a fixed portion of the 60 structure and connected to the moving span by a flexible connection pivotally attached to said counterweight and carried around and supported by a curved member on said moving span of such curvature that the heel 65 counter-balance and the counterweight together balance the bridge in all its positions.

To better accomplish the objects of my invention I prefer to place the counterweight pivot lower than the counterweight, so that 70 the counterweight moves in an arc above the horizontal line through its pivot and need not descend below its pivot, and I so shape and place the curved member supporting the counterweight connection that it continually 75 changes the angular position of said connection, during motion of the bridge, and simultaneously varies the lever arms of said connection about the pivot of the bridge and the pivot of the counterweight in a 80 proper relationship to effect the balance of the bridge in all its positions, and this I am enabled to do, under these novel conditions, by means of a method discovered by me and 85 fully described hereinafter, but not herein claimed.

My construction is especially useful when concrete is used for counter-balance, which is now the general practice, as, on account of its great bulk, concrete counter-balance is 90 very clumsy and unsightly when placed above the bridge deck.

Referring to the drawings which accompany the specification to aid the description:

Figure 1 is a side view of a bridge according to my construction.

Fig. 2 is a diagram explanatory of the method of laying out the curve of balance.

Fig. 3 shows a special case, and Fig. 4 is a view showing a truss bridge with the counterweight placed above the deck level.

Similar letters of reference refer to similar parts in all the figures.

Referring to Fig. 1, B is a bascule bridge, P the pivot or trunnion above which it rotates. A, A², A³ are piers and D a portion

of the fixed structure supporting said pivot P. Other parts of the fixed structure are omitted or are broken away for clearness.

H is the heel counter-balance forming a part of and rotating with the bridge B. W is a counterweight supported on a counter-weight support or arm K carried by and rotating about a pivot L placed in a convenient position on some fixed part of the structure, as the pier A.

C is a counterweight connection pivotally attached at a convenient point E on said arm K and also attached at a point I on said bridge B at or near said pivot P.

Said connection C passes around and is supported by the curve F. Said curve F forms a part of and rotates with said bridge B, and is of such form as to cause said weight W to move in a manner to complete the balance of said bridge B in all its positions, as is hereinafter explained in connection with Fig. 2.

The point C. g. is the position of the center of gravity of the combined weights of the bridge B and heel counterbalance H. Said center of gravity may be brought, by adjustment of the amount of the counterbalance H, to as near to the pivot P as is convenient, and hereinafter we will for brevity use the term "bridge" as referring to the total mass, including the counterbalance H, rotating about the pivot P. G is the center of gravity or center of mass of the counterweight W, which we will refer to hereinafter as the "center G" to avoid confusion with the center of gravity C. g. of the bridge. R and R', are respectively the fixed and movable portions of the roadway or bridge floor and Z is the break in the floor between them, which, as well as the heel counterbalance H, should be preferably so located as to clear the top of pier A, when the bridge is in a vertical position.

It will be understood that the description refers to one side of the bridge only and that the parts described will in general be duplicated on the other side of the bridge, but the heel counterbalance H and the counterweight W may extend clear across the bridge if desired.

The counterweight connection C may be of wire rope, chains or any other suitable construction, but I prefer to make it in part of a series of pivoted links as indicated on the drawings.

The bridge may be operated in any suitable manner, but I prefer to use a gear segment M secured to the bridge and meshing with a pinion N on shaft O, supported on a fixed part of the structure; and shaft O may be rotated by any suitable gearing and power.

When said pinion N is rotated in the direction the reverse of the hands of a clock,

the free end of said bridge B rises and the heel end descends, the connection C unwraps from said curve F and the said arm K and weight W descend, and when said pinion N is rotated in the opposite direction said bridge B descends and said weight W rises.

Analytical solution of the curve F is too complicated for practical use and the curve can best be formed by the graphic method hereinafter described.

Tangents to the curve F cannot readily be laid out by determining the lever arm of said tangents from a simple equation and by a method such as is illustrated and described, in my United States Patent, No. 1,151,657, and dated August 31st, 1915, because the weight W moves in an arc and the angular position and tension on the connection C vary for every position of the bridge, as also do the lever arms of said connection both about the pivot of the bridge and the pivot of the counterweight, and therefore I resort to the principle of virtual work in order to lay out said curves. The use of this principle gives great latitude in the choice of position of the various parts and greatly assists in the design of the bridge, as the limitation usually deemed necessary of making the angular motion of the arm K and weight W equal to the angular motion of the bridge is entirely avoided. In order that a movable bridge shall be balanced in all its positions, it is only necessary that for every position of the movement of the bridge the work of the parts which rise shall be equalled by the work of the parts which descend, *i. e.* the total work must equal zero. Hence when the center of gravity of the bridge C. g. rises any vertical distance h , and the center G of the weight W falls a vertical distance h' , then, if B and W are used to represent the respective weights of the bridge and the weight W, the relation required for balance is that $Bh + Wh' = 0$. Any mechanism whatsoever connecting the weight W to bridge B, which will maintain this relationship, will cause the bridge to be balanced in all its positions, and it is an object of this invention to produce such a mechanism.

It may be stated as a broad principle that for all bascule bridges having a tensional connection between the counterweight and moving bridge, the member supporting said connection will fulfil the above conditions and cause the bridge to be balanced in all its positions when said member is the evolute of the curve traced by any point of said connection when said connection is properly placed in all its positions relatively to the moving bridge considered as fixed in position, and I have found that if the nature of the structure is such that the required motion of any point on the counterweight connection (such as E, Fig. 1) can be deter-

mined, by means of the principle of virtual work, then the curve of motion of this point relatively to the bridge can be traced and a member which is the evolute of the curve so traced will effect the balance of the bridge in all its positions.

The following graphic method is an application of this principle—

Referring to Fig. 2, having determined the position of the center of gravity, C. g. of the bridge including the heel counterbalance H, and the total weight corresponding to said center of gravity, I swing an arc through C. g. with the pivot P as a center, 10 making said arc equal to the angular motion of the bridge, and longer if necessary to bring said C. g. vertically over the pivot P, whether the bridge may move so far or not, as said vertical position 10 of C. g. is important in the construction of the curve F, 20 as will be explained hereinafter.

I divide this arc into a convenient number of parts thus obtaining the positions 2, 3, 4, etc., of C. g., and including the vertical position 10 of C. g. I then draw a horizontal line C. g.—a through the primary position 1 of C. g. and vertical lines to said horizontal line from the other positions, 2, 3, 4, etc. Then said vertical lines h^2 , h^3 , h^4 , etc., represent the vertical heights through which the C. g. of the bridge moves in reaching its successive positions, and the work of the bridge in attaining said successive positions, will be its total weight B, multiplied by the heights h^2 , h^3 , etc.; said heights may be scaled from the drawing, or may be calculated trigonometrically.

Having chosen a suitable amount for the weight W, which I prefer to determine by dividing the work of the bridge in rising to its highest position by the height the said weight may be conveniently allowed to descend, I divide the work of the bridge for its various positions 1, 2, and 3, etc., by the weight of the weight W, in accordance with the general equation given above and so determine the corresponding vertical distances through which the center G of said weight W must descend in order to balance the bridge. I then draw horizontal lines at said distances h^2 , h^3 , h^4 below the primary position of said center G, and then swing an arc through said center G from the pivot L as a center, and the intersections of this arc with said horizontal lines give the various required positions g^2 , g^3 , g^4 , etc., of said center G, corresponding with the positions 2, 3, 4, etc., of C. g. Having selected a convenient point E for the attachment of the counterweight connection C to the arm K, I swing an arc through said point E from L as a center and locate on said arc the various positions e^2 , e^3 , e^4 , etc., of said point E, corresponding to the various positions g^2 , g^3 ,

g^4 , g^5 of the point G. The positions so found are the various required positions of said point E relatively to the fixed structure, but are not their positions relatively to the bridge itself, which also has moved. I then draw arcs through said points e^2 , e^3 , e^4 , e^5 , etc., from the pivot P as a center, and lay off on said arcs, but in the reverse direction, distances corresponding to the angular motions of the bridge and thus obtain a series of points f^2 , f^3 , f^4 , etc., which are the relative positions of the point E, with respect to the bridge itself, said bridge B being considered as fixed in position.

It will be found that said series of points E— f^2 , f^3 , f^4 , etc., lie in a curve of cycloidal form relatively to the pivot P, of the bridge. Choosing the point f^10 which corresponds to the position 10 of the bridge, when its center of gravity C. g. is vertically above the pivot, in which position the moment of the bridge around its pivot P is equal to zero, and therefore the moment of the counterweight connection C around said pivot must also be equal to zero, and therefore the line of pull of said connection C must pass through the pivot P, we draw the line f^10 —P, which is the relative position of the connection C for this position of the bridge and is a tangent to the curve F. The line f^10 —P, is the length of the connection C, measured from the point f^10 to the pivot P, and as obviously said connection C must be of constant length, the length from the pivot P to each of the points E, f^2 , f^3 , etc., measuring around the curve F must be constant and equal to the length of the said line P— f^10 , and therefore the curve F is the evolute of the curve E, f^2 , f^3 — f^10 , and therefore by drawing normals in the usual manner to said latter curve we obtain a series of lines t^1 , t^2 , t^3 , etc., which are tangents to said curve F, and by drawing a curve to said tangents, we obtain the required curve F.

The correctness of the curve F so found is of course dependent upon the number of positions taken, the scale of the drawing, and the care with which the graphic processes are performed; and I prefer to check the correctness of the positions of the various tangents by the method of moments. This can now be easily done, as the positions of the tangents and their lever arms are determined by the curve F, found as above described, and therefore the tensions in the connection C in its various positions can now be readily computed in the usual manner.

It will be understood that the curve F as found above is the theoretical center or pitch line of the connection C, and that the actual curve as constructed on the bridge must allow for the thickness of said connection.

In the usual design of bridges as described,

the center of gravity C. g. of the bridge will rarely rotate beyond the vertical position 10 and the counterweight connection C may be fastened at a convenient point I on the tangent P, f10; but said point I may be located off the said tangent line if desired, so as to produce a counter moment to aid in bringing the bridge to rest in its upper position. In cases where a balance is required beyond the vertical position 10, a sufficiently long section of curve tangent to said line P, f10 and reversed in position to the curve F may be used.

In Fig. 1 the connection C is shown as composed of numerous links and the curve F is continuous. This is necessary when great accuracy of balance is required, but in many cases a sufficiently accurate balance for practical purposes can be obtained by using a few long links as shown in Fig. 3, by n, r, s, and in Fig. 4 by u, v, w. In such cases the curve F need not be continuous, but may preferably consist of short segments at and supporting the joints of said connection as shown in Fig. 3. In small bridges a practical balance may often be attained with a single link, and the curve F may be then considered as of such small radius as to be the equivalent of a simple pivot or pin.

Cases occasionally occur where, on account of very limited vertical height, or on account of the necessary size of the weight W, we can not conveniently place the said weight W entirely beneath the floor of the bridge B, as is shown in Fig. 1, and in such cases the top of the weight W may be placed at the floor level as shown in Fig. 3, and extend across the bridge and form a part of the bridge floor when in normal position.

The distribution of counter-balance between the heel of the bridge and the counterweight W depends on the conditions of each particular case, and it will often be desirable to place all the counter-balance in the weight W and none in the heel of the bridge, as indicated in Fig. 3.

With the construction shown in Figs. 1 and 3, suitable locks are necessary to hold the bridge in its lowered position. These are well known in the art and are not specifically part of this invention, and are therefore not shown in said figures.

My invention is not limited to cases where the counter-balancing devices are placed below the bridge deck, though especially valuable in such cases, for the weight W, arm K and its pivot L may be placed above said deck and the invention may be applied to an ordinary truss bridge as shown in Fig. 4. In such cases, (see Fig. 4) I prefer to place the pivot P at the extreme end of the bridge, and to make the weight W suffi-

ciently heavy to completely balance the bridge. The drawings show single leaf bridges only, but it will be understood that this invention applies equally well to double leaf bridges.

By referring to the drawings, it will be noted that the angular movements of the counterweight W are not equal to the angular movements of the bridge, and that the total angular motion of the counterweight is substantially less than the total angular motion of the bridge, and that the moments of the counterweight about its pivot are not equal to the moments of the bridge about its pivot. The method herein described enables the form of the curve F to be determined under these conditions, and is specially useful in the cases shown where the counterweight and its path are above the horizontal line through the counterweight pivot.

Obviously the tensional connection may be pivotally connected to the moving span and the curved supporting member placed on the counterweight, the curved member is then the evolute of the curve formed by the span end of the tensional connection when rotated about the counterweight, considered as fixed, but this arrangement usually produces awkward structures of no great practical value.

Now having described my improvements, I claim as my invention.

1. In a bascule bridge, the combination of a pivoted bridge, a counterweight pivoted to a fixed support at a point lower than said counterweight, a tensional connection from said counterweight to said bridge and means having a curved surface supporting said connection to vary the lever arms of said connection about the pivot of said bridge and the pivot of said counterweight to effect the balance of said bridge in all its positions, substantially as described.

2. In a bascule bridge, the combination of a pivoted span, a counterweight, an arm carrying said counterweight and pivoted to a fixed support at a point lower than said counterweight, a tensional connection from said arm to said span, and means having a curved surface supporting said connection on said span and varying the lever arms of said connection about the pivot of said span and the pivot of said counterweight as said span and said counterweight rotate about their pivots to effect the balance of said span in all its positions, substantially as described.

3. In a bascule bridge, a pivoted span, a counterweight, an arm carrying said counterweight and pivoted to a fixed support, a tensional connection from said arm to said span and means having a curved surface supporting said connection and varying the lever arms of said connection about the pivot

of said span and the pivot of said counter-weight to balance said span in all its positions, the lever arm of said counterweight about its pivot increasing as the lever arm of said span about its pivot decreases, substantially as described.

Signed at New York city, in the county

of New York, and State of New York, this
11th day of November, A. D. 1916.

THOMAS E. BROWN.
